UNITED STATES PATENT OFFICE.

FRED C. HANNAHS, OF KENOSHA, WISCONSIN, ASSIGNOR OF ONE-HALF TO
JOHNSON A. JACKSON, OF SAME PLACE.

DESIGN FOR A CRIB OR CRADLE-BODY.

SPECIFICATION forming part of Design No. 21,531, dated May 10, 1892.

Application filed March 18, 1892. Serial No. 425,481. Term of patent 7 years.

To all whom it may concern:

Be it known that I, FRED C. HANNAHS, of Kenosha, in the county of Kenosha and State of Wisconsin, have invented a new and useful 5 Design for a Crib, Cradle-Body, or Similar Article of Furniture, of which the following is a description, reference being had to the accompanying drawing, which is a part of this specification.

10 The figure of the drawing represents a perspective view of my design for a crib, cradle-body, or similar article of furniture.

The leading feature of my design consists 15 in a crib, cradle-body, or similar article of furniture provided with a certain ornamentation of the posts, rails, and filling spindles or lattice, as hereinafter more fully described.

20 Referring to the drawing, the letters A A indicate the head-posts, and B B the foot-posts, said posts formed with an outline of connected convexo-convex surfaces.

The letters C C indicate the top rails, which are also of the same general contour. The

different spaces are filled by lattice-work consisting of spindles D of convexo-convex form. 25 These spindles, as clearly shown in the drawing, are arranged in horizontal and vertical lines, the points or ends of the several vertical spindles joining the horizontal spindles at their centers, and likewise the ends of the several horizontal spindles joining the vertical ones at their centers. It will also be seen that the same arrangement exists where the spindles connect with the posts and rails—that is to say, they join the same at their centers. 30 35

I claim—

The design for a crib, cradle-body, or similar article of furniture, substantially as herein shown and described.

In testimony whereof I affix my signature in presence of two witnesses.

FRED C. HANNAHS.
